COMPONENT CHECKING BURNER
CONTROL APPARATUS

John E. Lundberg, Minneapolis, Minn., assignor
to Minneapolis-Honeywell Regulator Company,
Minneapolis, Minn., a corporation of Delaware

Application September 15, 1950, Serial No. 184,975

6 Claims. (Cl. 158—28)

1

The present invention relates to an improved fuel burner control apparatus. More particularly, the present invention is concerned with a control apparatus which will maintain a controlled fuel burner inoperative in the event there is a flame failure or a false indication of flame.

In present day fuel burner controls, it has been found desirable to provide safety devices which will render the controlled burner inoperative in the event that combustion fails to take place when the burner is started, in the event that combustion fails after having once been initiated, or in the event that the control apparatus indicates falsely that there is combustion taking place at the burner. In a Patent 2,537,294 of John M. Wilson for "Component Checking Circuit For Burner Control Apparatus," and assigned to the same assignee as the present invention, there is disclosed an arrangement where a fuel burner is rendered inoperative in the event there is a flame failure or in the event that there is a false indication of flame by the flame detecting device. In either event, the burner control will maintain the burner inoperative until such time as the fault has been removed from the control apparatus and it is possible to have sustained combustion without having the safety cutout device of the apparatus shut the system down.

The present invention is concerned with a burner control apparatus of the type disclosed in the Wilson application and constitutes an improvement thereof. The present invention provides a special arrangement of the electrical circuit which will give maximum safe operation under conditions where there is a tendency for contacts of a flame responsive switching device to become dirty or contaminated. This is accomplished by so interconnecting switch contacts of the control apparatus that, upon the presence of combustion an actuator of a safety cutout device of the apparatus is open circuited when flame is present and, when flame is not present, it is impossible to initiate burner operation or energization of the burner control device unless contacts of the flame responsive switching device are making good electrical contact.

It is therefore an object of the present invention to provide a new and improved burner control apparatus which is effective to maintain the controlled burner inoperative in the event there is a combustion failure or there is a false indication of flame.

Another object of the present invention is to provide an improved burner control apparatus wherein maximum safe operation may be ob-

2

tained under circumstances where the flame switch contacts may become dirty or contaminated.

Still another object of the present invention is to provide a new and improved burner control apparatus wherein a safety cutout device having an electric actuator therefor is provided for shutting down the burner apparatus in the event there is a flame failure or a false indication of flame and open circuiting the actuator of the safety cutout device when the apparatus is operating properly.

These and other objects of the present invention will be understood upon a consideration of the following specification, claims, and the drawings appended hereto, of which:

Figure 1 is a diagrammatic showing of the present invention, and:

Figure 2 shows the circuit of Figure 1 in simplified form.

Referring to Figure 1, there is shown a fuel burner 10 which is arranged to be controlled by a thermostatic device 11 acting through appropriate control circuits in a control device indicated generally by the numeral 12. A photocell 13 is also used to affect the operation of the control circuits within the housing 12 and to effect burner shutdown conditions when there has been a flame failure with the burner in operation.

Referring to the control circuits within the housing 12, the numeral 15 represents a power transformer which supplies power to the subject control circuit. This transformer comprises a primary winding 16, a secondary winding 17, and a further secondary winding 18. The secondary winding 17 is tapped at 19. The winding 17 supplies power to effect the operation of a control relay 20. This control relay 20 comprises a relay coil 21, a pair of switch blades 22 and 23, and switch contacts 24, 25 and 26. When the relay coil 21 is deenergized, the switch blades 22 and 23 are normally biased out of engagement, by means not shown, from the contacts 24 and 26 and the blade 22 is biased into engagement with the contact 25.

Also included in the energizing circuits of the relay 20 is a safety cutout device 30. This cutout device 30 comprises a pair of switch contacts 31 and 32 which are normally maintained in engagement by a bimetallic member 33. For actuating or warping the bimetallic member 33, a heater 34 is provided and is mounted adjacent the bimetal. A reset operator 35 is provided for moving the contacts 31 and 32 into engagement after the heater 34 has caused the bimetal 33 to

move out from under the contacts 31 and 32 to permit the same to open.

The secondary winding 18 is used to supply power to a suitable flame detection device of the electronic type which may be of the type disclosed in the R. S. Feigal Patent 2,556,961 assigned to the same assignee as the present invention. The subject flame detector is so arranged that an output control relay, such as relay 42 will move to the energized position whenever a flame is detected at the burner 10 by the photoelectric device 13. The relay 42 comprises a relay coil 43, a switch blade 44 normally biased out of engagement with a resilient contact 45, a switch blade 46 normally biased into engagement with a resilient contact 47, and a switch blade 48 that is normally biased into engagement with an associated contact 49. The switch blades 44 and 46 and their associated contacts 45 and 47 are so arranged that the contacts are overlapping when the relay moves from the deenergized to the energized position or from the energized to the deenergized position. In other words, when the relay 42 becomes energized the switch blade 44 will move into engagement with the contact 45 before the switch blade 46 moves out of engagement with its associated contact 47.

If desired, a suitable ignition device 50 may be provided at the burner 10. However, the apparatus may be utilized with controls which have constant ignition or ignition by standing pilot flames.

Operation

In considering the operation of the present apparatus, assume first that the thermostatic device 11 is not demanding operation of the burner 10 and the apparatus is in the completely deenergized position. When in the deenergized position the apparatus will be shown as it is in the drawing in Figure 1.

Upon the space wherein the thermostatic device 11 is located cooling, to indicate a need for burner operation, the contacts of the thermostatic device will close and an energizing circuit for the relay 20 will be completed. This energizing circuit may be traced from the upper terminal of secondary 17 through safety cutout device contacts 32 and 31, conductor 60, relay coil 21, conductor 61, thermostatic device 11, conductor 62, switch contact 47, switch blade 46, conductor 63, conductor 64, heater 34 and conductor 65 back to the lower terminal of the secondary 17. When the circuit is completed, the relay coil will cause the switch blades 22 and 23 to move into engagement with their associated contacts 24 and 26 respectively. When the switch blade 23 engages contact 26, an energizing circuit is completed to the burner 10. This circuit may be traced from an input power line 70 through conductor 71, switch contact 26, switch blade 23, conductor 72, burner 10, and conductor 73 back to the other input power line 75. An energizing circuit will also be completed to the ignition device 50 and this energizing circuit may be traced from the input power line 70 through conductor 71, switch contact 26, switch blade 23, conductor 72, switch blade 48, switch contact 49, conductor 76, ignition device 50, and conductor 73 back to the other input power line 75.

As soon as the burner flame is established at the burner 10 and the same is detected by the photocell 13, the flame detection device 40 will be operative to energize the relay 42. When the relay 42 becomes energized switch blades 44 and

46 will be moved from the deenergized position and, since the contacts are overlapping, the electrical circuits associated therewith will remain closed until such time as the switch blade 44 engages contact 45. When the switch blade 44 engages contact 45 a holding circuit for the relay 20 is established and this holding circuit includes the switch blade 22 and contact 24 of the relay 20. The holding circuit may be traced from the upper terminal of the secondary 17 through switch contacts 32 and 31, conductor 60, relay coil 21, conductor 61, thermostatic device 11, switch contact 24, switch blade 22, switch contact 45, switch blade 44, and conductor 78 back to the tap 19 on secondary 17. When the switch blade 22 moved out of engagement with contact 25 and the switch blade 46 moved out of engagement with contact 47, the energizing circuit to the heater 34 was broken so that the heater will no longer be effective to tend to warp the bimetal 33 and cause opening of the contacts 31 and 32. When the switch blade 48 moved out of engagement with contact 49, the energizing circuit to the ignition device 50 was broken.

The apparatus is now in the operating position and, when in the operating position, the safety switch heater will be open circuited to prevent shutting down of the apparatus and the apparatus will remain in this mode of operation until such time as there is no longer a call for operation of the burner by the thermostatic device 11 or there is a flame failure at the burner. The operation upon a flame failure will be considered below. If the thermostatic device 11 no longer indicates a need for operation of the burner, the energizing circuit to the relay 20 will be open circuited upon the opening of the thermostatic device contacts. As soon as the relay 20 becomes deenergized, the switch blades 22 and 23 will move to the deenergized position and the burner circuit will be interrupted. As soon as the burner circuit is interrupted the flame will no longer be detected by the flame detector 40 and the relay 42 will move to the deenergized position. As soon as the relay 42 is deenergized the apparatus will return to the position in which it is shown upon the drawing in Figure 1.

Operation upon flame failure

In considering the operation upon flame failure, first consider that there has been a demand for burner operation by the closing of the contacts to the thermostatic device 11. The closing of these contacts will cause the energization of the relay 20 by a circuit which has been traced above. When the relay 20 does become energized the burner 10 and ignition device 50 will become energized, as also traced above. It will be recalled that the energizing circuit for the relay 20 can be traced through the heater 34 of the safety cutout device 30. This energizing circuit is more conveniently shown in Figure 2 where the circuit may be traced from the right hand terminal of the secondary 17 through the safety cutout contacts 31 and 32, relay coil 21, thermostatic device 11, switch contacts 47 and 46, and heater 34 back to the left hand terminal of the secondary 17. When the relay 20 becomes energized the contacts 22 and 24 will move into engagement and the contacts 22 and 25 will move out of engagement. This latter movement of the contacts 22 and 24, and 22 and 25 will not have any immediate effect upon the energizing circuit of the relay 20 as the contacts 44 and 45 will remain open and it will be impossible to complete any electrical circuit by the contacts 22 and 25, or

22 and 24. If a flame is not detected at the burner by the photocell 13 so that the flame detector 40 does not energize relay 42, the contacts of the relay 42 will remain in the position in which they are shown in Figure 2 as well as in Figure 1. This will mean that the energizing circuit for the relay 20 will be continued through the heater 24.

Continued energization of the heater 34 will cause the bimetal 33 to move out from under the contacts 31 and 32 and the contacts will open. When the contacts 31 and 32 open, the energizing circuit for the relay 20 will be broken and the apparatus will go to a shutdown position and will remain in that position until such time as the manual reset button 35 is depressed to place the contacts 31 and 32 back in the closed position so that a further starting attempt may be made when the contacts of the thermostatic device 11 are closed.

Should the apparatus start up normally with flame present and there should be a subsequent flame failure, the relay 42 will move to the de-energized position and the energizing circuit for the relay 20 will again be completed through the heater 34 in the circuit which was traced above in connection with a flame failure on start. As long as this heater 34 is energized, the bimetal 33 will be warped so as to cause opening of the contacts 31 and 32 and there will again be a shutdown as explained above.

It should be noted that in both of the situations that have been described in connection with the flame failure that upon the opening of the safety switch contacts 31 and 32 the energizing circuit to the heater 34 is interrupted so that there will be no further heating of the heater and as soon as the bimetal 33 is cooled sufficiently, depressing of the start button 35 will cause closing of the contacts 31 and 32.

Operation upon a false indication of flame

Whenever a situation exists in the control apparatus that the flame detection relay 42 is in the energized position when in fact there is no flame present at the burner 10, it is desired that the apparatus be shut down and be maintained in a shutdown condition until such time as the fault causing false operation of the relay 42 has been removed. The need for such an arrangement can be understood when it is noted that the flame detection device 40 includes electronic discharge devices which normally require an appreciable period of time for heating and coming into operation. For purposes of explanation assume there is no call for heat and the flame detection device 40 has developed a fault which causes the relay 42 to be energized when in fact no flame is present at burner 10. If a power failure now occurs the electron discharge devices of flame detector 40 cool and relay 42 becomes deenergized. When a burner control apparatus is used which does not have the component checking feature, upon a call for heat and the subsequent restoration of power, due to the fact that the flame detection apparatus 40 includes electron discharge devices which must be heated to their operating temperature before relay 42 can be energized, the relay 42 will pull in after the relay 20 has pulled in as though the apparatus were starting as in a normal start with the relay 20 pulling in first and the relay 42 subsequently pulling in to indicate the presence of burner flame.

To protect against such conditions wherein

5 false operation of the flame detection relay 42 will permit operation of the system without adequate flame supervision, a special circuit arrangement is provided for energizing the safety switch heater 34 whenever there is a false operation of the relay 42 when there is no demand for burner operation by the thermostatic device 11, thus opening the contacts 31 and 32 to prevent relay 20 from being energized after a power failure and a call for heat during the power failure.

Referring to either Figure 1 or Figure 2, assume that the thermostatic device 11 is not calling for burner operation so that there will be no energizing circuit completed for the relay 20. Assume further that there is a false indication of burner flame by the relay 42 so that the relay is in the energized position. When the relay 20 is in the deenergized position, the contacts of the relay are as shown in the drawing with contacts 22 and 25 closed and contacts 22 and 24 open. When the relay 42 is indicating the presence of flame it will be in the energized position and when energized the contacts 44 and 45 will be closed and the contacts 46 and 47 will be open. When contacts 44 and 45 are closed and 22 and 25 are closed, an energizing circuit will be completed to the heater 34 and this energizing circuit may be traced from the tap 19 of secondary 17 through the switch contact 44, switch contact 45, switch contact 22, switch contact 25, and heater 34 back to the end terminal of the secondary 17. As long as this circuit remains energized there will be heat supplied to the heater 34 and, after a predetermined time, the heater 34 will cause contacts 31 and 32 to open. When the contacts open, it will be impossible to energize the relay 20 upon subsequent closing of the thermostatic device 11. It will be noted that the energizing circuit for the heater 34 is independent of the contacts 31 and 32 under the present circumstances and even though the contacts 31 and 32 open, the heater 34 will remain energized and therefore the bimetal 33 will remain in a warped position so that it will be impossible to reclose the contacts 31 and 32 until such time as the energizing circuit to the heater 34 is broken. This can be accomplished only by causing the relay 42 to move to a deenergized position and removing the fault which is causing the false operation of the relay. As soon as the fault causing false operation of the relay is removed, the apparatus can be operated as explained above during the normal operation.

Conclusion

55 From the foregoing it will be seen that a burner control apparatus has been provided which will shut down the burner in the event that there is a false operation of the flame detection relay or a flame failure. It will also be noted that the apparatus is so arranged that when operating normally the electrical circuit to the heater 34 of the safety switch device 30 is open circuited so that it is impossible for the current to flow therethrough. In prior component checking burner control apparatus it is possible to energize the heater of the safety switch when the apparatus and burner are functioning normally since the safety switch heater is shorted instead of open circuited, therefore, in the event that the shorting contacts become contaminated or dirty sufficient current will flow through the heater to cause the safety switch to operate when in fact a flame is present at the burner being controlled. It should further be noted that in the event that

if the contacts of the relay 42 become contaminated so that when contacts 46 and 47 should be engaging upon a flame failure when the relay 42 moves to the deenergized position, it will be impossible to establish an energizing circuit for the relay 21 as the moving of the relay 42 to the deenergized position causes opening of the contacts 44 and 45 and this will deenergize the relay 20. When relay 20 is deenergized the contacts 22 and 24 will open so that the only energizing circuit for the relay 20 has to be through the contacts 46 and 47. If these contacts are not making proper electrical contact it will be impossible to energize the control relay 20.

Inasmuch as many modifications to the present apparatus can be made by one skilled in the art without departing from the teachings thereof, it is intended that the scope of the invention be limited solely by the appended claims.

I claim as my invention:

1. Control apparatus for a fuel burner, comprising, a source of power, a control relay having a relay coil and a first pair of switch contacts which are closed when the relay coil is deenergized and a second pair of switch contacts which are closed when the relay coil is energized, said relay adapted to cause energization of the fuel burner upon becoming energized, a safety cutout device having means including a heater arranged to open a pair of safety contacts after a predetermined period of energization, a combustion responsive switching mechanism having a pair of contacts which are closed when there is no combustion and a pair of contacts which are closed when there is combustion, said contacts of said switching mechanism being overlapping with changing position, an energizing circuit for said relay coil including said source of power, said heater, said pair of contacts of said switching mechanism which are closed when there is no combustion, and said pair of safety contacts, a holding circuit for said relay coil when combustion is present including a portion of said source of power, said second pair of switch contacts of said control relay, and said pair of contacts of said switching mechanism which are closed when there is combustion, said heater being open circuited when said pair of contacts of said switching mechanism, closed when no combustion is present, are opened, and an energizing circuit for said heater when there is a false indication of the presence of combustion, said circuit including a second portion of said source of power, said first pair of contacts of said control relay, and said pair of contacts of said switching mechanism which are closed when combustion is present.

2. Control apparatus for a fuel burner, comprising, a control relay having contact actuating means and having a first pair of contacts closed when said relay contact actuating means is deenergized and a second pair of contacts which are closed when the relay contact actuating means is energized, means controlled by said relay adapted to complete an energizing circuit for the fuel burner when said relay is energized, a source of power having two end terminals and a tap, a combustion responsive switching mechanism having a first pair of contacts closed when no combustion is present and a second pair of contacts closed when combustion is present, a safety cutout device having an electrical actuator and a pair of cutout contacts, a circuit for connecting said end terminals of said source of power in en-

ergizing relation to said relay contact actuating means including said pair of cutout contacts, the first pair of contacts of said switching mechanism, and the actuator of said cutout device, a holding circuit for connecting said relay contact actuating means to said tap and one end terminal of said source of power and including the second pair of contacts of said control relay and the second pair of contacts of said switching mechanism, and an energizing circuit for the actuator of said cutout device when there is a false indication of combustion including said source of power, the second pair of contacts of said switching mechanism, and the first pair of contacts of said relay.

3. Control apparatus for a fuel burner, comprising, a control relay having contact actuating means and having a first pair of contacts which are closed when said relay contact actuating means is deenergized and a second pair of contacts which are closed when the relay contact actuating means is energized, means controlled by said relay adapted to complete an energizing circuit for the fuel burner when said relay is energized, a source of power having two end terminals and a tap, a combustion responsive switching mechanism having a first pair of contacts which are closed when no combustion is present and a second pair of contacts which are closed when combustion is present, a safety cutout device having an electrical actuator and a pair of cutout contacts, a circuit for connecting said end terminals of said source of power in energizing relation to said relay contact actuating means including said pair of cutout contacts, the first pair of contacts of said switching mechanism, and the actuator of said cutout device, a holding circuit for connecting said relay contact actuating means to said tap and one end terminal of said source of power and including the second pair of contacts of said relay and the second pair of contacts of said switching mechanism, the actuator of said cutout device when said holding circuit is complete being electrically open circuited to prevent further energization thereof, and an energizing circuit for the actuator of said cutout device when there is a false indication of combustion including said source of power, the second pair of contacts of said switching mechanism, and the first pair of contacts of said relay.

4. Control apparatus for a fuel burner comprising, a control relay having contact actuating means and having a first pair of contacts which are closed when the relay contact actuating means is deenergized and a second pair of contacts which are closed when the relay contact actuating means is energized, means controlled by said relay adapted to complete an energizing circuit for the fuel burner when said relay is energized, a source of power having two end terminals and a tap, a combustion responsive switching mechanism having a first pair of contacts closed when no combustion is present and a second pair of contacts closed when combustion is present, means connecting the first and second pair of contacts of said relay to electrically separate the first pair of contacts of said switching mechanism from the second pair of contacts of said switching mechanism, a safety cutout device having an electrical actuator and a pair of cutout contacts, a circuit for connecting said end terminals of said source of power in energizing relation to said relay contact actuating means including said pair of cutout contacts, the first pair of contacts of said switching mechanism, and the actuator of said cutout device, a holding circuit for connecting said relay contact actuating means to said tap and one end terminal of said source of power and including the second pair of contacts of said relay and the second pair of contacts of said switching mechanism, the actuator of said cutout device when said holding circuit is complete being electrically open circuited to prevent further energization thereof, and an energizing circuit for the actuator of said cutout device when there is a false indication of combustion including said source of power, the second pair of contacts of said switching mechanism, and the first pair of contacts of said relay.

tacts of said switching mechanism, and the actuator of said cutout device, a holding circuit for connecting said relay contact actuating means to said tap and one end terminal of said source of power and including the second pair of contacts of said relay and the second pair of contacts of said switching mechanism, and an energizing circuit for the actuator of said cutout device when there is a false indication of combustion including said source of power, the second pair of contacts of said switching mechanism, and the first pair of contacts of said relay.

5. In a burner control apparatus, a source of power, a safety switch device having a pair of switch contacts and a heater therefor which is operative to cause opening of said safety switch contacts upon continued energization for a predetermined length of time to effect deenergization of said control apparatus, a thermostatic switch adapted to be closed upon indication of a need for burner operation, a first relay having in and out switch contacts, said relay adapted to cause energization of the burner upon becoming energized, a second relay having overlapping in and out switch contacts, said second relay normally being rendered operative upon proper operation of the burner, a first electric circuit for energizing said first relay, said circuit including said thermostatic switch, said safety switch contacts, the out switch contacts of said overlapping switch contacts, said safety switch heater and said source of power, a second electric circuit for maintaining said first relay energized independently of said safety switch heater and adapted to be completed without interruption of the energization of said relay, said second circuit including said thermostatic switch, the in contacts of said overlapping contacts, in contacts of said first relay and said source of power, and a third electric circuit adapted to be completed through 35 said safety switch heater upon said first relay becoming deenergized and said second relay remaining in energized position, said third circuit including the in contacts of said overlapping contacts, out contacts of said first relay, and said source of power.

6. In a burner control apparatus, a source of

power, a safety switch device having a pair of switch contacts and a heater therefor which is operative to cause opening of said safety switch contacts upon continued energization for a predetermined length of time to effect deenergization of said control apparatus, a control circuit adapted to be closed upon an indication for need of operation of the burner, a first relay having in and out switch contacts, said relay adapted to cause energization of the burner upon becoming energized, a second relay having overlapping in and out switch contacts, said second relay normally being rendered operative upon proper operation of the burner, a first electric circuit for energizing said first relay, said circuit including said control circuit, said safety switch contacts, the out switch contacts of said overlapping switch contacts, said safety switch heater, and said source of power, a second electric circuit for maintaining said first relay energized independently of said safety switch heater and adapted to be completed without interruption of the energization of said relay, said second circuit including said control circuit, the in contacts of said overlapping contacts, in contacts of said first relay, and said source of power, a third electric circuit adapted to be completed through said safety switch heater upon said first relay becoming deenergized and said second relay remaining in energized position, said third circuit including the in contacts of said overlapping contacts, out contacts of said first relay, and said source of power.
